US0D1109702S

(12) **United States Design Patent** (10) Patent No.: **US D1,109,702 S**
(45) Date of Patent: ** Jan. 20, 2026

(54) **CLIP FOR OPTICAL FIBER CONNECTORS**

(71) Applicant: **Hakusan Inc.**, Ishikawa (JP)

(72) Inventors: **Motohito Takezaki**, Kanazawa (JP);
Shohei Ueno, Kanazawa (JP)

(73) Assignee: **Hakusan Inc.**, Ishikawa (JP)

(**) Term: **15 Years**

(21) Appl. No.: **35/522,816**

(22) Filed: **Oct. 31, 2023**

(80) **Hague Agreement Data**

Int. Filing Date: **Oct. 31, 2023**
